CLAIM

The ornamental design for a communication device with keyboard, as shown and described.

DESCRIPTION

FIG. 1 is a top perspective view of the communication device with keyboard showing our new design;

FIG. 2 is a bottom perspective view thereof;

FIG. 3 is a back view thereof;

FIG. 4 is a front view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a top perspective view of the open position thereof;

FIG. 10 is a bottom perspective view of the open position thereof;

FIG. 11 is a back view of the open position thereof;

FIG. 12 is a front view of the open position thereof;

FIG. 13 is a right side elevation view of the open position thereof;

FIG. 14 is a left side elevation view of the open position thereof;

FIG. 15 is a top plan view of the open position thereof;

FIG. 16 is a bottom plan view of the open position thereof; and,

FIG. 17 is a cross section view of FIG. 1.

In the drawings, the broken-line showing of buttons depicts environmental subject matter only and forms no part of the claimed design. In FIG. 17, the innermost dashed line represents a boundary for the claimed region and is not intended to indicate environmental subject matter. This indicates that only the perimeter line in FIG. 17 is part of the claimed design.
